CLAIM

The ornamental design for a servo motor, as shown and described.

DESCRIPTION

FIG. 1 is a front perspective view of my design for a servo motor;

FIG. 2 is a front elevation view thereof;

FIG. 3 is a back elevation view thereof;

FIG. 4 is a right side elevation view thereof;

FIG. 5 is a top plan view thereof; and,

FIG. 6 is a bottom plan view thereof.

The right side is symmetrical to the left side.

In the drawings, the broken lines illustrate portions of the servo motor and form no part of the claimed design.
